FRITTING FURNACE

Application filed November 15, 1929. Serial No. 407,428.

This invention relates to improvements in fritting furnaces and has particular reference to a furnace utilized for the production of glaze employed as a coating for ceramic bodies.

An object of the invention is to facilitate the fritting process to which the glaze material is customarily subjected in the preparation of the final product, by so constructing and mounting the crucible into which the material is fed that the source of heat utilized to produce the fritting operation will come into direct contact with said crucible and thereby cause a more rapid liquefaction of said material.

Another object is to provide a construction of crucible and burner which will permit of the liquefied material from the former to feed by gravity therefrom directly through the burner and its combustion chamber into a crystallization pan.

The above and other objects will appear more clearly from the following detailed description, when taken in connection with the accompanying drawings, which illustrate a preferred embodiment of the inventive idea.

In the drawings—

Figure 1 is a vertical longitudinal section through a fritting furnace constructed in accordance with the invention;

Figure 2 is a transverse section on the line 2—2 of Figure 1; and

Figure 3 is a similar section on the line 3—3 of Figure 1.

The furnace is shown as comprising a supporting framework 5, to the upper end of which is secured the body 6 of the furnace which may be made of any suitable refractory material surrounded by the insulation 7 which is, in turn, enclosed in a metallic casting 8.

Within the body 6 there is formed a crucible-receiving chamber 9 opening through the bottom of said body and having an exhaust flue 10 at its top through which pass the

gases of combustion from the burner 11 which has its casing supported beneath the body 6 in communication with the chamber 9. Formed on the inner wall of said chamber are a plurality of opposed supporting flanges 12, the inner edges of which converge downwardly toward the opening in the body 6. Said edges are so formed and spaced from each other as to conform to the contour of and accurately center and support the crucible 13 within the chamber 9, whereby the same will be positioned directly above the combustion chamber 14 of the burner 11 so that the flame from the latter will come into direct contact with practically the entire surface of said crucible, that is the portions thereof between said flanges, thus quickly and thoroughly heating the same. To further facilitate the heating action, the crucible is of inverted conical formation with the apex thereof acting to spread the flame to all exposed parts of the surface of the crucible. An inlet pipe 15 is provided for the crucible which extends upwardly from the upper end thereof and through the top of the body 6. Through this pipe, the glaze material is continuously fed into the crucible body where it is fritted by the action of the heat applied to said body. As the material is liquefied it slowly feeds, by gravity, through a small outlet opening 16 formed in the apex of the crucible 13 and drips downwardly into a pan 17 located below the burner 11, said pan containing water in which the fritted material crystallizes, following which it is pulverized in any well-known manner.

The burner 11 comprises a casting 18 having a central opening 19 therethrough which is in vertical alignment with the opening 16 in the crucible so that the drippings therefrom will pass through said opening 19 and drop into the pan 17, thereby affording a direct path for the liquid from the crucible downwardly through the combustion chamber and the burner casting into said pan.

The casting further includes the burner coil 20 and trough 21 for receiving oil from the feed pipe 22. Fitted into the upper end of the opening 19 and having an opening 23 aligned therewith and with the outlet 16 is a spreader 24 which assists in creating a proper flame in the chamber 14. The casing 11 of the burner is open at its bottom for the admission of preheated air into the chamber 14 and an additional air inlet 25 may be provided in the side of said casing.

What is claimed is:

1. A fritting furnace comprising a body, an apertured crucible in said body, a burner beneath said body having a combustion chamber, a burner element in said chamber having an opening therethrough in vertical alignment with the aperture in said crucible, and a flame spreader supported by said burner element and having an opening therein aligned with the opening in said element.
2. A fritting furnace comprising a body, an apertured crucible in said body, a burner element beneath said crucible and having an opening therein through which material from said apertured crucible will flow, and a flame spreader supported by said burner element and also having an opening therein through which said material will flow.

33 In testimony whereof we have affixed our signatures.

JOHN F. RYAN.
CHARLES STEGMAYER.
